WITNESS:

John D. Moran

ATTORNEY

UNITED STATES PATENT OFFICE.

THOMAS HARRY KIRKPATRICK, OF FARGO, NORTH DAKOTA.

INK PAN.

Application filed March 5, 1928. Serial No. 259,326.

- My present invention has reference to line 5
ruling machines, such as are commonly em-
ployed in printing plants and the like for
scribing parallel lines of different colors
upon sheets of paper, the present improve-
ment being primarily directed to the ink
pan for such machines, and the means for
delivering ink from the pans to the scribing
pens.
- 10 The primary object of the invention is to
secure over the pen clamp as well as upon
the beam clamp any desired number of su-
perimposed ink pans, secured together in a
novel manner whereby the rear of the pans
15 will remain open so that different colored
inks can be fed into the several pans and
further wherein each of the pans has ar-
ranged in its bottom an absorbent sheet,
against which rests one end of a capillary
20 agent whose opposite ends are connected
each with one of the scribing pens and
whereby ink will be delivered to the pens
in an easy and steady manner without the
liability of over or underfeeding the same,
25 with the result that clear, sharp and solid
lines of uniform thickness will be scribed
on the paper.
- For a full and comprehensive understand-
ing of the invention reference is to be had
30 to the accompanying drawings which form
part of this application.
- In the drawings:
- Figure 1 is a top plan view of the im-
provement in applied position.
- 35 Figure 2 is a sectional view approximately
on the line 2—2 of Figure 1.
- In the drawings I have not deemed it
necessary to illustrate the ink delivery means
40 for the several pans, nor have I deemed it
necessary to illustrate a complete line ruling
machine. The beam of the machine is,
in the drawings, indicated by the numeral
1, the said beam being provided with the
usual round opening that affords a bearing
45 for the pivot member 2. The beam, at what
may be termed its forward end is longitudi-
nally notched to form the same with a
groove 3 and in this groove there is received
a tongue 4 on the upper element 5 of the pen
50 clamp. The lower element or block 6 of the
pen clamp is secured to the upper element
through the medium of screws which have
knurled heads 7 and the tongue 4 is retained
in the groove 3 by similar screws or bolts 8.
- 55 The outer or nose end of the clamp is round-
ed and there is arranged in suitable depres-
sions between the parts 5 and 6 of the clamp
the inner and straight ends 9 of the scribing
pens 10. Passing through the upper ele-
ment 5 of the pen clamp adjacent to the 60
ends thereof there are bolts 11. These bolts
also pass through openings in bosses 12 pro-
vided on the inner ends of substantially rec-
tangular pans 13. As disclosed by the draw-
ings the pans are arranged in superimposed 65
relation, that is, one pan rests on the other,
but the bosses 12 are so arranged that what
may be termed the rear of the pans are open,
and these openings provide means whereby
different colored ink may be fed into the 70
individual pans 13. The uppermost pan is
partly closed by a plate 14, and screwed upon
the bolts 11 and contacting with the plate
14 there are knurled nuts 15.
- Resting on the bottom of each of the pans 75
13 there is a sheet of felt or like fabric ma-
terial 16, and passing through the forward
end of each pan and having its inner end
resting upon the sheet 16 there is a capillary
80 agent 17. The capillary agents 17 are each
in the nature of a string and are preferably
formed of a yarn. The elements 17 may be
hollow and, therefore, are in the nature of
tubes. Each of the elements 17 is connected,
85 as at 18, to one of the scribing pens 10.
- The different colored inks in the several
pans 13, being directed onto the fabric pads
16, will be siphoned therefrom by the ele-
ments 17 by a capillary attraction so that
the ink will be fed to the several scribing 90
pens 10 in an easy and steady manner with-
out the liability of over or under feeding of
the said pens and the result is that the paper
19 which is fed beneath the pens will have
95 inscribed thereon clear, sharp, and solid lines
of uniform thickness.
- Having described the invention, I claim:
1. In a device for the purpose set forth,
the combination of a tiltable beam having a
sectional pen clamp removably secured 100
thereto, and scribing pens secured to and
depending from the clamp, superimposed
ink receiving pans resting on the beam and
clamp and removably secured thereto, each
105 of said pans being of a different width
whereby the rear of each of the pans is
partly open, a plate partly covering the top
of the uppermost pan, each of said pans
having a sheet of fabric in the bottom there-
of and tubular capillary agents having one 110

of their ends resting on the said sheet, directed through the top of the pans, clamped thereon by the bottom of the superimposed pan and the mentioned plate and directed 5 toward and secured to the respective scribing pens.

2. In a device for the purpose set forth, the combination with a tilttable beam having a groove in the outer face thereof, a two- 10 part clamp having a tongue received in the groove, adjustable means for securing the tongue in the groove, bolts for connecting the parts of the clamp, scribing pens having straight ends secured between the parts of 15 the clamp, and bolts secured to and projecting upwardly from adjacent the ends of the upper element of the clamps, superimposed ink receiving pans, the lowermost

of which resting on the top of the clamp and the beam, said pans having their inner faces 20 adjacent their ends formed with bosses through which the mentioned bolts pass, said pans being so arranged that the rear portions thereof are partly open, a plate upon the uppermost pan for partially closing the same, nuts screwed on the bolts and contacting with the plate, a fabric sheet resting in the bottom of the pan, and tubular members of absorbent material clamped by 25 the superimposed pans and plate, resting on the sheets, directed toward and attached to the respective scribing pens, for the purpose set forth.

In testimony whereof I affix my signature.
THOMAS HARRY KIRKPATRICK.
